MULTI-PURPOSE PRESS

Robert E. Lancaster, Minneapolis, Minn.

Application August 7, 1952, Serial No. 303,043

4 Claims. (Cl. 100—269)

This invention relates to a multi-purpose press and more particularly to an industrial type of press in which the press beam is simultaneously actuated at a multiplicity of points.

There have been a number of presses in the nature of bending brakes and shear presses which employ such actuators as multiple hydraulic rams to operate the mechanism. There is, however, a fundamental problem which must be solved in all these multiple cylindered presses, namely to provide for equal pressure upon the hydraulic rams in order to maintain the press beam in alignment as it is descending toward the press bed. The longer the press beam and the greater the amount of work required of the press, the more critical is this matter of alignment. In some cases as little as one-sixteenth of an inch differential between the advancement of one hydraulic ram over the other can cause binding of the bearing surfaces. Further misalignment may permanently injure the press itself, and particularly the parts which constitute the hydraulic rams. As far as the inventor is aware, all the attempts to rectify this problem in the past have been directed toward control of the hydraulic pressure as it is applied to the multiple cylinders, the compensation for uneven travel of the press beam being made while it is in motion. As a consequence, inventors have centered upon various devices for differentially treating the movement of the multiple rams allowing only for small misalignment of the order which will not cause permanent damage to the hydraulic press. The present invention proposes to employ manually controlled valve means for admitting hydraulic fluid to each hydraulic ram independently or simultaneously, no attempt being made to automatically compensate for any slight misalignment of the press beam as it travels toward or away from the press bed.

In a conventional mechanical press that uses multiple actuators the same problem exists, but to a lesser degree. Since there is positive mechanical connection at each of the actuating points, adjustments may be made mechanically to prevent uneven advancement of the press beam. Aligning the beam, however, often throws off the even application of pressure to the work. In any event, so far as I am aware, there are no successful presses, either hydraulic or mechanical, which can be converted easily and simply from a shear press to a press brake and vice versa.

It is therefore a general object of the invention to provide for means whereby an industrial press having a press beam actuated at a multiplicity of points can be usefully employed without danger of damaging equipment whether or not the press beam is misaligned with respect to the rest of the press structure.

Since my multi-purpose press can operate successfully even during misalignment of the press beam I may utilize this very situation for converting the press from a press brake to a shear press with simple and economical changes which can be accomplished with a minimum of manpower and time. It is therefore another object of this invention to provide for a press of the class described wherein male and female dies may be mounted upon the press beam

2

and press bed for use as a press brake or where, at the operator's wishes, the entire press may be converted to a shear press by substituting shear blades for the die members, all with a rapid and simple adjustment despite heavy-duty characteristics of the press.

It is a still further object of the invention to provide for stop means to prevent unnecessary forward travel of the press beam when approaching the press bed, particularly of a hydraulic press. When used as a shear press both ends of the press beam are stopped at a point just beyond the completion of the shearing operation. This shortening of unnecessary movement will facilitate the return of the press beam to its beginning position and therefore increase the rate of which the cycle of operations may be performed. When my press is used as a press brake, each end of the press beam is stopped at exactly the predetermined point in order to obtain the desired bend in the sheet of metal without thinning and unnecessarily working the metal. Such measure is found extremely useful when bending soft and thin metals, especially aluminum and magnesium alloys. In previous heavy duty presses having a long span at the press beam, such thin and soft metals have been thinned out by unnecessary pressure after the bending is completed so as to cause the finished work to warp and otherwise not conform to specifications. Consequently it is a still further object of the invention to provide for stop means to prevent unnecessary forward travel of the press beam when approaching the press bed, particularly of a hydraulic press.

These and other objects and advantages of my invention will more fully appear from the following description made in connection with the accompanying drawings wherein like reference characters refer to similar parts throughout the several views and in which:

Fig. 1 is a front elevation of my multi-purpose press showing the essential outline thereof with the press beam in full line to show its position when used as a press brake and in dotted line configuration to show the corresponding lower end thereof when used as a shear press;

Fig. 2 is a segmental vertical section of the bearing assembly at the left hand end of the hydraulic press;

Fig. 3 is a segmental detailed view of the right bearing assembly with the lift links in place but the cover plate removed to show the relationship of the trackway to the bearing assembly;

Fig. 4 is a segmental horizontal section taken on the lines 4—4 of Fig. 3;

Fig. 5 is a segmental view of the right bearing assembly with the spacer block in position for shearing operation; and

Fig. 6 is a vertical section of a segment of the press beam and press bed showing details of hold-down structure and shear blade assembly.

Referring now more particularly to the drawings, the press illustrated is a hydraulic press of conventional structure. The supporting framework S comprises a lower portion to which the bed 10 is rigidly secured and spaced parallel uprights 11 at the left and 12 at the right are joined at the top in a head brace 13 as shown in Fig. 1. The press beam 14 operates in a general direction toward and away from the press bed 10 to effect the particular press operation desired. The standard or upright 12 comprising the right part of the supporting structure S has housed

therein a trackway which may be constructed of angles 15 as shown in Fig. 4. These angle irons 15 are secured as by bolts 16 to the upright or standard 12 which in turn comprises side plates 17 at the outer end and 18 at the inner end thereof. Cross plates 19 at the rear end 20 at the fore complete the housing containing the trackway. Openings 21 in each of the angle irons 15 may be slightly larger than the diameter of bolt 16 so

as to allow for slight adjusting movement. Thus, in setting the tracks at their desired adjusted position the nuts 22 may be drawn down against the outer surface of the standard or upright 12 and then slightly loosened so as to give a slight play thereto. Set screws 23 are then screwed inwardly through corresponding threaded openings 24 in the plates 19 and 20 so as to bring the angle irons 15 to their final desired adjustment. The nuts 22 are then tightened finally so as to maintain the trackway in rigid position with close tolerances of the surfaces therebetween.

Slidably mounted within the trackway is a first bearing assembly comprising an upper bearing block 25 having guide members 26 at the sides thereof for positioning the bearing block 25 in non-rotatable cooperation with the trackway during vertical reciprocation therein. The bottom of the upper bearing block is arcuate in shape and is of a width sufficient to form a substantial bearing surface with the upper rocker block 27 which is of similar width and the identical arcuate curvature. Although it is possible to practice my invention by having both ends of the press beam 14 in slidable engagement with the rocker blocks, I prefer to have the beam anchored as shown in Fig. 3. Thus, the side extension 28 is secured to the rocker block 27 at its underneath surface as by welding. A lower rocker block 29 is similarly attached to the lower side extension 28. The arcuate surface of lower rocker block 29 and that of the upper rocker block 27 form portions of a circle having its center coincident with the axis of pin 30 which is disposed transversely of the press beam 14 at the side extension 28 and projecting for a short distance to either side thereof. In bearing engagement with the arcuate surface of the lower rocker block 29 is the lower bearing and stop block 31. This bearing block has guide members 32 at either side thereof for positioning in the trackway in the same manner as the upper bearing block 25. A pin 33 extends for a short distance on either side of the lower bearing block 31 for engagement with a pair of lift links 34 which maintain the entire first bearing assembly in loose relative position preparatory to pressing engagement between the bearing surfaces thereof. The links 34 have openings 35 and 36 at the lower end as shown in Fig. 3 and openings 37 and 38 at an intermediate position. The upper ends of lift links 34 have openings 39 which are adapted to be engaged by the reduced end portions 40 of the cross head 41 which in turn is rigidly secured to the piston rod 42 of the hydraulic ram mechanism R. The cross head 41 is cradled in a trough 43 formed across the upper surface of bearing block 25. The actuating means such as hydraulic ram devices R, details of which are not shown, may be housed one within each of the standards as shown in Fig. 1. It is intended that bearing block 25 with which the hydraulic ram is in bearing engagement, will not have any shifting relative to the ram cross head 41. However, in order to alleviate strains placed upon the bearing assembly due to slight play between the various parts thereof and the trackway, I have found it desirable to employ the cross head and cradle arrangement.

Adjustably mounted within the standard or upright 12 is a stop member 44 which can be raised or lowered to form an abutting stop for the first bearing assembly when the underside of lower bearing block 31 comes operably into contact therewith.

Referring now to Fig. 2 a second bearing assembly is mounted in the standard or upright 11 at the left side of my press so as to cooperate with the first bearing assembly during the operation of the device. Similarly to the first assembly a hydraulic ram R is rigidly mounted within the standard or upright 11 and has depending therefrom a reciprocable piston rod 42 and assembly cross head 41 at the lower end thereof. An upper bearing block 45 is slidably mounted within a trackway comprising angles 15 which are adjustable for close tolerances

as previously described in connection with the trackway in upright 12. The lower surface of the upper bearing block 45 is arcuate but not necessarily with the same rate of curvature as that employed by the upper bearing block 25 in the first bearing assembly. Also, unlike the first bearing assembly, the upper rocker block 46 is not rigidly connected to the left side extension 47 of the press beam 14, but is in sliding engagement therewith through a bearing plate 48 which may be attached to the surface of side extension 47 in contact with the upper rocker block 46. It is found desirable under the tremendous pressures employed to have dissimilar metals in bearing contact. Thus, I may employ a cast steel block 46 and a hard bronze plate 48 to reduce the high pressure friction therebetween. Similarly, the lower rocker block 49 is in sliding engagement with a bearing plate 50 which may be attached to the underside of the side extension 47. Rocker block 49 also has an arcuate surface in bearing engagement with lower bearing and stop block 51 which is vertically slidable with close tolerance in the left trackway in standard or upright 11. Adjustably mounted within the upright 11 is a stop member 52 which can be vertically positioned to prevent the downward movement of the second bearing assembly after the lower bearing block 51 has come in engagement therewith. A pair of lift links 53 the foremost one of which lies forwardly of the vertical section plane of Fig. 2 in opposite relation to the rear link which appears in the drawing are disposed between the cross head 41 and the pin 33 in the lower bearing block 51, which cross head, and pin are counterparts of those parts associated with the first named bearing assembly, so as to maintain the second bearing assembly in loose relative position during upward movement of the hydraulic ram and in preparation for engagement of the parts during downward bearing operation thereof. The press bed 10 may have a shearing assembly 54 removably secured thereto for cooperation with an opposed shearing assembly 55 removably secured to the underside of press beam 14 as shown in Fig. 6. It is understood, of course, that various types of shearing elements as well as dies for forming may be attached to my multiple purpose hydraulic press. Hold-down mechanism 56 of conventional structure may be mounted upon the press beam 14 and adapted to cooperate with the table member 57 attached in turn to the press bed 10 adjacent the shear assembly 54. The opposed hold-down members 56 and 57 may be swingably mounted so as to be retractable at will.

Referring now to Fig. 5, when it is desired to employ my hydraulic press as a shear press I deliberately depress the right hand end of the press beam 14 by inserting a spacer block 58 between the bearing block 25 and the upper rocker block 27. I then simultaneously adjust the lift links 34 so that opening 37 now engages the pin 30 which is affixed to the side extension 28 of the press beam 14. The opening 37 as well as all the other openings in the lift links are slightly larger than the pins so as to merely hold the bearing assemblies in loose relation during the lifting thereof. Lower bearing block 31 and its pin 33 are likewise repositioned to the opening 35 in the lift links 34. When thus assembled, the first bearing assembly will function the same as previously except that the entire press beam 14 will be several inches lower at the right end as shown by the dotted line configuration in Fig. 1. With the spacer block removed the press beam will assume a horizontal position as indicated by the full line configuration.

During the operation of my hydraulic press I may mount suitable cooperating dies for such purpose as forming thin aluminum sheet materials. The male and female dies (not shown) are mounted in the normal manner with the press beam 14 in the horizontal or full line position shown in Fig. 1. I then adjust the stop members 44 and 52 so as to prevent the beam from traveling beyond the point at which the forming is complete. Thus, I am not concerned whether the right or left ram

has slightly more pressure than the other nor whether one ram is traveling slightly ahead of the other. When the forming operation is complete there will be no thinning nor warping of the sheet because of unnecessary pressure at one side or the other. It may, of course, become necessary to readjust one or the other of the stop members 44 or 52 to gain exactly the desired result. During the travel of the press beam and during the application of pressure to the work, any misalignment of the press beam at one end or the other is compensated for by shifting of the press beam itself and not by the hydraulic ram nor of the press structure. Thus, referring to Figs. 2 and 3, supposing the second bearing assembly shown in Fig. 2 should lag slightly behind the travel of the first bearing assembly shown in Fig. 3. In this event, the entire press beam 14 will rock imperceptibly about the axis of pin 30 with the arcuate surfaces of the bearing blocks adjusting themselves accordingly. If the bearing block 31 has not yet engaged its adjustable stop 44 the assembly will shift or rock without actual bearing contact. It will, of course, be in proper position for bearing as soon as contact is established between the die on press beam 14 and the work (not shown) and will so maintain its contact until the stop 44 is contacted. While this slight pivoting is taking place at the first bearing assembly the other side extension 47 of the press beam 14 will retract a very short distance between the rocker blocks 46 and 49 and will thus remain retracted by its imperceptible degree until the rams become aligned or until the lower bearing block 51 contacts the adjustable stop 52. If there is relative shifting during the actual forming operation under high pressure it becomes essential that the side stresses in the hydraulic rams and the press structure be relieved. Relief is obtained, of course, by the pivoting bearing action at the right or first bearing assembly and by the sliding action of the press beam within the rocker blocks 46 and 49 at the left or second bearing assembly. Although the pivoting and shifting may be so slight as to not be observable it still may be sufficient to prevent the build-up of tremendous stresses upon the rams and press structure. Thus, by placing the stress where it belongs, namely on the exact longitudinal axis of the piston rods and vertically throughout both bearing assemblies I can achieve a much higher working pressure with a lesser degree of structural strength in the press and in the parts of the press ram.

Where I desire to use the versatile press as a shear press I may remove the lift links 34 from the first or right bearing assembly and insert the spacer block 58 as shown in Fig. 5. I then reassemble the first bearing assembly with the openings of the lift links 34 in their new position as previously described. With the right end of the press beam 14 depressed as in the dotted line configuration of Fig. 1, I now operate simultaneously the rams in the standards or uprights 11 and 12 in the same manner as before with the lowered relation of the right end being maintained throughout the operation. In this instance I likewise lower the adjustable stop member 44 by the width of the spacer block 58 so as to prevent excessive travel of the shear blade which has been attached to the press beam 14. The shear blade will contact the work at the right end and progress toward the left end in a manner similar to that in conventional shear presses. Hold-down elements 56 and 57 may be employed during the shearing operation as is common to the art. Here again misalignments of the individual rams will have no disastrous effect upon the work or upon the machine itself, the press beam 14 merely pivoting at the first bearing assembly and sliding at the second bearing assembly in the manner previously noted. As the press beam completes the shearing operation, the lowered adjustment stop 44 and the adjustment stop 52 will prevent unnecessary travel of the press beam. This stopping of the beam will result in greater work produc-

tion because the time required to return the press beam to its upper position will not be so great for each cycle. I have found that much of the operation time that is lost in standard press beam equipment is due to this unnecessary travel of the shear blade, especially in its downward travel after the shearing operation is completed.

It will, of course, be understood that various changes may be made in the form, details, arrangement and proportions of the parts without departing from the scope of my invention.

What I claim is:

1. In a multi-purpose press device having a supporting structure including a rigid bed and parallel uprights secured thereto in spaced relation, an actuator mounted on each of said uprights and movable downwardly and upwardly along said upright, a first bearing assembly comprising an upper bearing block, an upper rocker block, a lower rocker block and a stop block, a lift link interconnecting the actuator and the stop block of said first bearing assembly, a second bearing assembly comprising an upper bearing block, an upper rocker block, a lower rocker block and a stop block, a lift link connected between the other actuator and the stop block of said second bearing assembly, and a press beam secured at one end to the rocker blocks of said first bearing assembly and having its other end slidably engaged between the upper and lower rocker blocks of said second bearing assembly.
2. A multi-purpose press comprising a supporting structure having spaced parallel trackways and a rigid press bed secured thereto, a first bearing assembly slidably mounted in one of said trackways, a second bearing assembly slidably mounted in another of said trackways, actuator means mounted on said supporting structure and connecting with said first and second bearing assemblies for imparting working force thereon, a press beam mounted across said first and second bearing assemblies and having a curved upper surface at one end for arcuate pivotal bearing connection with the first bearing assembly, said one end of the press beam having its side surfaces in sliding engagement with its trackway, said press beam having a flat upper surface at the other end thereof and the side surfaces thereof lying in sliding engagement with the trackway with the second bearing assembly associated therewith, said second bearing assembly having pressing and sliding engagement with said flat upper surface, and removable spacer means between the curved bearing surface of said press beam and the bearing surface of said first bearing assembly.
3. In a multi-purpose press device having a supporting structure including a rigid bed and parallel uprights secured thereto in spaced relation, an actuator mounted on each of said uprights and movable downwardly and upwardly along said upright, a first bearing assembly comprising an upper bearing block, an upper rocker block, a lower rocker block and a stop block, a lift link interconnecting the actuator and the stop block of said first bearing assembly, a second bearing assembly comprising an upper bearing block, an upper rocker block, a lower rocker block and a stop block, a lift link connected between the other actuator and the stop block of said second bearing assembly, and a press beam secured at one end to the rocker blocks of said first bearing assembly and having its other end slidably engaged between the upper and lower rocker blocks of said second bearing assembly, said lift link having a plurality of spaced fastening means, the spacing of one pair of the fastening means being such as to hold the first bearing assembly in close association for raising the beam, and another pair of said fastening means being utilized to create a space in said bearing assembly to permit positioning a spacer block in close association between a rocker block and one of said bearing and stop blocks.
4. In a multi-purpose hydraulic press device having

a supporting structure including a rigid bed and parallel uprights secured thereto in spaced relation, an actuator mounted on each of said uprights and movable downwardly and upwardly therealong, a first bearing assembly comprising a bearing block connected to one of said actuators, an upper rocker block, a lower rocker block and a stop block, a second bearing assembly having a bearing block connected to the other of said actuators, an upper rocker block, a lower rocker block and a stop block, a press beam rigidly secured to the upper and lower 10 rocker blocks of said first bearing assembly at one end thereof and at the other end thereof in slidably bearing engagement between the upper and lower rocker blocks of the second bearing assembly, and a spacer block of predetermined width interposed between the 15 bearing block and the upper rocker block of said first

bearing assembly whereby the end of the press beam which is in contact with the first bearing assembly will be lower than the other end by the width of the spacer block.
